FIG. 6 is a top view thereof;
FIG. 7 is a bottom view thereof;
FIG. 8 is a front perspective view of a connector housing showing a second embodiment of our new design;
FIG. 9 is a right side view thereof;
FIG. 10 is a left side view thereof;
FIG. 11 is a front view thereof;
FIG. 12 is a rear view thereof;
FIG. 13 is a top view thereof;
FIG. 14 is a bottom view thereof;
FIG. 15 is a front perspective view of a connector housing showing a third embodiment of our new design;
FIG. 16 is a right side view thereof;
FIG. 17 is a left side view thereof;
FIG. 18 is a front view thereof;
FIG. 19 is a rear view thereof;
FIG. 20 is a top view thereof;
FIG. 21 is a bottom view thereof;
FIG. 22 is a front perspective view of a connector housing showing a fourth embodiment of our new design;
FIG. 23 is a right side view thereof;
FIG. 24 is a left side view thereof;
FIG. 25 is a front view thereof;
FIG. 26 is a rear view thereof;
FIG. 27 is a top view thereof;
FIG. 28 is a bottom view thereof;
FIG. 29 is a front perspective view of a connector housing showing a fifth embodiment of our new design;
FIG. 30 is a right side view thereof;
FIG. 31 is a left side view thereof;
FIG. 32 is a front view thereof;
FIG. 33 is a rear view thereof;
FIG. 34 is a top view thereof;
FIG. 35 is a bottom view thereof;
FIG. 36 is a front perspective view of a connector housing showing a sixth embodiment of our new design;
